UNITED STATES PATENT OFFICE.

ABBY DAY SLOCOMB, OF GROTON, CONNECTICUT, ASSIGNOR TO J. E. CALDWELL & CO., OF PHILADELPHIA, PENNSYLVANIA.

DESIGN FOR A TABLE-BELL.

SPECIFICATION forming part of Design No. 26,629, dated February 16, 1897.

Application filed May 12, 1896. Serial No. 591,299. Term of patent 14 years.

To all whom it may concern:

Be it known that I, ABBY DAY SLOCOMB, a citizen of the United States, and a resident of Groton, New London county, Connecticut, have invented a certain new and useful Design for a Bell, of which the following is a specification.

My design for a table-bell is fully illustrated in the accompanying drawing, which represents a side view of the bell; and the main features of the design are the imitation of a petticoat as the body of the bell and a stem or handle having an imitation of a flagstaff.

The body portion A of the bell is made in the form of an extended petticoat of coarse material, having a border a at the base and a band b at the waist. This band b terminates in a bow, which is draped down one side of the petticoat, as shown.

The body of the bell is folded in imitation of the folds of the petticoat.

The stem or handle D of the bell projects from the waist of the petticoat and consists of a staff d with an ornamental head d' at the top, a square plate d² near the base, and cords d³, two at each side, extending from the top of the staff around the plate and secured to the staff under the plate. The ends of these cords extend down the side of the petticoat.

I claim—

The design for a table-bell as herein described and as shown in the accompanying drawing.

In testimony whereof I have signed my name to this specification in the presence of two subscribing witnesses.

ABBY DAY SLOCOMB.
